CLAMP

Guido E. Barozzi, Woodcliff, N. J.

Application April 22, 1937, Serial No. 138,362

1 Claim. (Cl. 24—84)

The invention relates primarily to the art of treating pelts and skins with particular reference to the stretching thereof for use by the furrier or other manufacturer. The object of the invention is to provide a novel and simple clamp whereby the stretching of the pelts and skins may be materially facilitated and improved. Other more specific objects will appear from the description hereinafter and the features of novelty will be pointed out in the claim.

In the accompanying drawing, which illustrates several examples of the invention without defining its limits, Fig. 1 is a fragmentary view of a supporting device designed to function as a drying unit and exemplifying the use of the novel clamp; Fig. 2 is a side elevation, partly in section, of one form of the novel clamp; Fig. 3 is a plan view thereof; Fig. 4 is a sectional view on the line 4—4 of Fig. 2; Fig. 5 is a side elevation of another form of the novel clamp, and Fig. 6 is a plan view thereof.

In the form illustrated in Figs. 2, 3 and 4, the novel clamp comprises a main section or member 10 terminating at one end in a clamping jaw 11 and continued at its other end in the form of a suitable finger-piece or handle 12. A support 13 of suitable shape and dimensions depends from the main section or member 10, preferably as an integral part thereof, while a projection or peg 14 extends downwardly from the finger-piece or handle 12 also preferably as an integral part thereof for the purpose to be more fully set forth hereinafter.

The clamp being described further consists of an auxiliary section 15 pivotally connected at 16 with the main section 10 and terminating in an associate clamping jaw 17 located in co-operative relation to the clamping jaw 11; to increase the gripping or clamping action of the jaws 11 and 17, the auxiliary section 15 or specifically the associate jaw 17, may be formed with teeth 18 or their equivalent, as illustrated in Fig. 2. Suitable means is provided for manipulating the auxiliary section 15 and for locking the clamping jaw 17 in operative clamping relation to the clamping jaw 11. As shown in Fig. 2, the aforesaid means may consist of a lever 19 pivotally connected at 20 with the one end of the auxiliary section 15, said lever 19 preferably being conveniently shaped to provide a finger-piece 21 whereby manual operation of said lever 19 is facilitated. For the purpose of developing a clamping action in the jaw 17 in co-operation with the jaw 11, and in order to lock the section 15 and its jaw 17 in clamping posi-

tion, the locking lever 19 is provided with a cam member or nose 22 adapted to bear against a suitable bearing surface or projection 23 preferably comprising an integral part of the finger-piece or handle 12 of the main section 10 as shown in Fig. 2; in some forms the bearing surface 23 may be omitted in which case the cam member or nose 22 may be arranged to bear directly upon the finger-piece or handle 12 of the main section 10 to lock the jaw 17 in clamp- 10 ing relation to the jaw 11.

With the parts as illustrated in Fig. 2, the lever 19 is in its operative position and the cam member or nose 22 in co-operation with the bearing surface or projection 23 will accordingly 15 lock the auxiliary section 15 against relative pivotal movement on the pivot 20 and thus maintain the associate clamping jaw 17 in clamping relation with the clamping jaw 11. The jaws 11 and 17 accordingly will firmly grip the pelt *a* or its equivalent, and thereby will securely connect the clamp with said pelt *a* as indicated in Fig. 2. To adjust the associate clamping jaw 17 to an inoperative position, or in other words, to disconnect the clamp from the pelt *a* or its equivalent, it is simply necessary to pivotally 20 adjust the lever 19 in the direction of the arrow in Fig. 2. This operation shifts the cam member or nose 22 out of bearing engagement with the bearing surface or projection 23 and thereby permits the auxiliary section or member 15 to move 25 pivotally in a direction which shifts the associate clamping jaw 17 away from the jaw 11 to relieve the clamping action of said jaws 11 and 17 on the pelt *a* or its equivalent, as will be apparent.

In the form illustrated in Figs. 5 and 6, the novel clamp consists of a main section or member 10^a, a portion of which serves as a clamping jaw 11^a corresponding to the clamping jaw 11 of Fig. 2. In the arrangement now being described the free end of the main section or member 10^a is curved or otherwise shaped to provide a support 13^a corresponding in function to the support 13 of Fig. 2 as will appear more clearly hereinafter. As illustrated in Fig. 4, the main section or member 10^a also includes a finger-piece or handle which is shown in the form of a ring 12^a and preferably constitutes an integral part of the main section or member 10^a. The form shown in Figs. 5 and 6 includes a projection or peg 14^a corresponding 40 to the previously described projection or peg 14 and likewise extending downwardly from the finger-piece or handle 12^a preferably as an integral part thereof.

For co-operation with the clamping jaw 11^a, the 45

50

55

clamp illustrated in Figs. 5 and 6 is provided with an associate clamping jaw 17^a which preferably constitutes an integral part of the means for manipulating the associate jaw 17^a and locking it in operative clamping relation to the clamping jaw 11^a. As in the form first described, the manipulating and locking means comprises a lever 19^a pivotally connected at 20^a with an auxiliary member or section 15^a; the latter as shown in Fig. 5 may constitute an integral part of the finger-piece or handle 12^a projecting therefrom in substantially parallel spaced relation to the main section or member 10^a. To facilitate the manual operation of the associate clamping jaw 17^a the locking lever 19^a may be conveniently shaped to provide a finger-piece 21^a.

With the parts as illustrated in Fig. 5, the lever 19^a is in its operative position and the associate clamping jaw 17^a is located in clamping relation with the clamping jaw 11^a. The jaws 11^a and 17^a accordingly will firmly grip the pelt *a* or its equivalent, and thereby will securely connect the clamp with said pelt *a* as indicated in Fig. 5. When it is desired to disconnect the clamp from the pelt *a* or its equivalent, it is simply necessary to pivotally actuate the lever 19^a in the direction of the arrow in Fig. 5. This operation of the lever 19^a will swing the associate jaw 17^a away from the jaw 11^a to thereby relieve the clamping action of said jaws 11^a and 17^a on the pelt *a* or its equivalent, as will be apparent.

In the art for which the novel clamp is specially designed, it is customary to mount the pelts upon a supporting device consisting of a metallic or other plate *b* provided throughout its surface with perforations *c* and preferably mounted in a frame *d*. This supporting device with the pelts mounted thereon is then placed in a drying apparatus to serve as a drying unit for the purpose of drying the pelts or their equivalent. With the novel clamp operating in co-operation with the aforesaid supporting device, it is possible to effect the stretching of the pelts in an efficient manner during the drying process, thereby avoiding the necessity for special stretching of the skins as an independent operation as is now generally the case; the novel clamps further support the stretched pelt *a* in spaced relation to the plate *b* and thereby provides for an efficient circulation 45 of the drying medium relatively to the stretched pelt *a* whereby the drying thereof is materially facilitated.

In practice, the novel clamp is attached to the pelt *a* in such numbers and at such points of the pelt as may be necessary to produce the desired results. Some of the clamps, for instance those indicated as *e* in Fig. 1, are then connected with the supporting device by inserting the pegs 14 or 14^a of said clamps into certain apertures *c* of the plate *b*. The clamps *f* of Fig. 1 may then be used to stretch the pelt *a* to whatever extent may be desired or necessary, after which the pegs 14 or 14^a of the clamps *f* are likewise inserted into certain apertures *c* of the plate *b*. During the stretching of the pelts the finger-pieces 12 or 12^a make it possible to develop the pull necessary to effect the desired amount of stretch with a minimum of effort on the part of the operator. It

will be noted in the illustrated forms of the novel clamp that the finger-pieces 21 and 21^a of the locking levers 19 and 19^a respectively, are located in such relation to the finger-pieces 12 and 12^a that the thumb of the operator may be used to 5 press downwardly upon said finger-pieces 21 and 21^a while the pull is being exerted through the medium of the novel clamps. In this way the locking levers 19 and 19^a are maintained in their operative positions to correspondingly maintain 10 the clamping jaws in clamping position against accidental displacement and disconnection from the pelt *a*. In any case when the clamps attached to the pelt *a* are secured in place upon the plate *b* the support 13 or 13^a rests upon said plate 15 *b* are thereby support the stretched pelts *a* in spaced relation thereto. The drying medium is thus capable of freely circulating about the stretched pelts *a* whereby the drying thereof is greatly facilitated. The pegs 14 and 14^a constitute 20 means whereby the clamps are fixed in predetermined positions to efficiently maintain the pelts *a* in a stretched condition during the drying thereof.

In all of its forms the clamp itself is simple 25 in construction and requires no skill in its operation. The clamps are capable of being readily connected with and detached from the pelts *a* or their equivalent, at will, and provide an efficient means whereby the desired stretching pull may 30 be easily developed upon the pelt and whereby at the same time the stretched pelt may be efficiently fixed in its stretched condition, for instance, upon the perforated plate *b*. It will be noted that any pulling force exerted upon the 35 clamp of Fig. 5 when the latter is connected with a pelt *a* will be resisted by the latter and itself will operate to maintain and increase the gripping action of the jaws 11^a and 17^a. The novel clamp not only reduces the stretching operation 40 to its simplest form, but at the same time provides an efficient means for maintaining the pelt *a* or its equivalent, in stretched condition. The novel clamp furthermore enables the stretching of the pelts to be accomplished coincidentally with the 45 drying of said pelts and avoids the necessity for independent stretching operations which are now required.

Various changes in the specific forms shown and described may be made within the scope of 50 the claim without departing from the spirit of the invention.

I claim:

A clamp of the kind described comprising a main section including a clamping jaw, an auxiliary section pivotally connected with said main section and including an associate clamping jaw, a finger-piece forming a continuation of said main section and terminating in a holding peg, a bearing projection on said main section, a locking lever pivotally connected with said auxiliary section and including a cam member co-operating with said bearing projection to lock said associate jaw in clamping relation with said first named jaw, and a support depending from said main section for supporting the jaws of said clamp in predetermined operative position.

GUIDO E. BAROZZI.
